Fig. 3.

UNITED STATES PATENT OFFICE.

OTTO H. VAN AMBERG, OF SCHENECTADY, NEW YORK, ASSIGNOR TO GENERAL ELECTRIC COMPANY, A CORPORATION OF NEW YORK.

LIGHTING FIXTURE.

Application filed January 28, 1921. Serial No. 440,779.

The present invention relates to lighting fixtures such as wall brackets, ceiling fixtures, and the like, and particularly fixtures of the type wherein the wall or ceiling portion of the fixture comprises a wired unit and the bracket or hanging portion of the fixture comprises a second wired unit, the latter being adapted to be detachably connected mechanically and electrically to the former, the electrical connection being made by means of a receptacle and plug connection.

The object of my invention is to provide an improved structure and arrangement in apparatus of this character, and for a consideration of what I believe to be novel and my invention, attention is directed to the accompanying description and the claims appended thereto.

20 My invention relates more particularly to ceiling fixtures, and in the drawing I have illustrated it as embodied in such a fixture, but it will be understood that it is not necessarily limited thereto.

25 In the drawing, Fig. 1 is a face view of the ceiling portion of the fixture; Fig. 2 is a side elevation showing the bracket portion of the fixture attached to the ceiling portion; Fig. 3 is a plan view of the bracket portion of the fixture; and Fig. 4 is an exploded view thereof.

Referring to the drawing, 10 indicates the face plate of a flush plug receptacle and 11 a plug receptacle fastened to the rear side 35 of plate 10 by screws 12 and provided with the usual openings 13 in line with which are contacts 14. Plate 10 may be fastened to a wall or to a suitable outlet box by screws 15. This arrangement may be taken as 40 typical of any plug receptacle structure adapted to be fastened to a wall or to a ceiling, and permanently wired to the lighting circuit. In plate 10 on one side of receptacle 11 are two spaced openings 16 and 45 on the other side is an opening 17. Openings 13 are provided with extensions 18.

The foregoing forms what may be termed the wall portion of my improved fixture, it being understood that the term wall is 50 used in a generic sense as including either a side wall or a ceiling.

For co-operation with the wall portion of my fixture I provide a combined plug and supporting member which is permanently 55 wired, is adapted to support a lighting fix-

ture or bracket, and is adapted to be connected to and detached from the wall portion of the fixture in a simple and easy manner. At the same time, however, the mechanical connection is a strong one not likely 60 to become accidentally detached and imposes no strains on the electrical connections. The combined plug and supporting member comprises a mounting block 20 of insulating material to which are attached 65 two contacts or contact blades 21 by screws 22. The contacts have heads 23 located in grooves 24 in the mounting block and threaded into openings in heads 23 are binding screws 24^a for the circuit wires. At 70 the center of mounting block 20 is a sleeve 25 of insulating material through which and the mounting block is an opening 26 for the passage of the cord connector. Mounting block 20 is fastened in a metal casing 75 27 by screws 28. Casing 27 may be made of brass, for example, or other suitable metal, and is preferably somewhat longer than block 20 and has curved ends to give 80 it a pleasing contour. It is open on the side from which contacts 21 project, this being the side which goes against the face plate 10. At one end of casing 27 are two 85 projecting lugs or fingers 29 adapted to engage face plate 10 through openings 16 and at the other end is a spring pressed hook 30 pivoted on a shaft 31 and adapted to engage face plate 10 through opening 17. Hook 30 has an end 30^a which projects 90 through an opening in casing 27 and is used to release the catch.

Projecting downwardly from casing 27 is a pair of spaced ears 32 on which is pivoted a U-shaped yoke 33 which carries a threaded nipple 34. Ears 32 may be formed integral 95 with a strap 35 which is located in a transverse groove 36 in block 20, the ears projecting through slots 37 in casing 27. This arrangement provides a strong simple structure and one which is compact and easily 100 assembled. The arms of the U-shaped yoke 33 are of such length that when nipple 34 is vertical they engage the outer surface of casing 27. Such arms are cut away on one side, as indicated at 38, so casing 27 may 105 be turned at an angle to the nipple and the parts carried thereby, as shown in dotted lines in Fig. 2.

In use as a ceiling fixture, the face plate 10 and plug receptacle 11 are permanently 110

- fixed to a ceiling and wired to the lighting circuit. A lighting fixture such as a chandelier is fastened to nipple 32 by a suitable rod, a hook and chains, or other arrangement, and the lamp sockets of the lighting fixture are permanently wired to the plug contacts. In the present instance, a chandelier is indicated by pipe 40. To attach the hanging portion of the fixture to the wall portion, the combined plug and support is held at an angle to face plate 10 and lugs 29 are inserted into openings 16. The plug is then pushed or swung toward the face plate, lugs 29 pivoting on the edges of openings 16. During this movement contact blades 21 swing through the extension 18 of openings 13 and into engagement with contacts 14. As the surface of the plug moves into engagement with face plate 10, catch 30 enters opening 17 and locks over plate 10 at the edge of the opening, as shown in Fig. 2, the spring serving to bias the catch to locking position. The lighting fixture is then both mechanically and electrically connected to the wall portion of the fixture. To disconnect it, it is only necessary to release catch 30 by means of end 30^a and pull down on the catch end of casing 27. Since U-shaped yoke 33 is pivoted to casing 27, the casing may be turned at an angle to the yoke so that in connecting and disconnecting the lighting fixture the fixture as a whole need not be held at an angle to the face plate but only casing 27 and the plug. This enables the connection or disconnection to be made with the lighting fixture vertical, which makes it much easier to do.
- In carrying out my invention, I may utilize any suitable number of lugs 29 and any suitable number of catches 30, the essential thing being that the mechanical connection be strong enough to support the weight of the suspended fixture. In any event, there is no strain on the electrical connections. It is to be noted, furthermore, that by my invention, I modify existing structures but little. In the case of the wall portion of the fixture it is only necessary to provide the additional openings in the face plates and extensions of the receptacle openings. In the case of the hanging portion of the

fixture, any existing structure may be modified by supplying in connection with it the combined plug and supporting member.

In accordance with the provisions of the patent statutes, I have described the principle of operation of my invention, together with the apparatus which I now consider to represent the best embodiment thereof, but I desire to have it understood that the apparatus shown is only illustrative and the invention may be carried out by other means.

What I claim as new and desire to secure by Letters Patent of the United States, is:

1. In a wiring fixture, the combination with a face plate, and a plug receptacle associated therewith, said face plate being provided with spaced openings and said receptacle being provided with contacts, of a combined plug and supporting member comprising a metal casing, a mounting block fixed in the casing, blade contacts carried by said block, a lug and a latch carried by the casing, said lug and latch being adapted to engage the face plate through said face plate openings, and a pivoted member connected to the casing and adapted to support a lighting fixture.

2. In a wiring fixture, the combination with a face plate, and a plug receptacle associated therewith, said face plate being provided with spaced openings and said receptacle with elongated openings with contacts in line therewith, of a combined plug and supporting member comprising a metal casing, a mounting block fixed in the casing, blade contacts carried by said block, a lug and a latch carried by the casing, said lug being adapted to be inserted at an angle into one of said face plate openings and the member then turned on the wall forming an edge of the opening as a pivot to bring the latch into engagement with the face plate through another of said face plate openings and the blade contacts into engagement with the receptacle contacts, a pair of ears projecting from said casing, and a lighting fixture pivoted to said ears.

In witness whereof, I have hereunto set my hand this 26th day of January, 1921.

OTTO H. VAN AMBERG.
